COMBINED ILLUMINABLE DISPLAY SIGN AND CLOCK

Virgil Smith, 837 S. Westgate, Los Angeles, Calif.

Filed Sept. 27, 1963, Ser. No. 76,755

Term of patent 14 years

(Cl. D1—12)

FIG. 1

FIG. 2

FIG. 3

FIG. 4

FIG. 5

FIG. 6

FIG. 1 is a perspective view showing a combined illuminable display sign and clock, said view illustrating my new design;

FIG. 2 is a top plan view thereof;

FIG. 3 is a bottom plan view thereof;

FIG. 4 is a rear elevational view thereof;

FIG. 5 is a right side elevational view thereof; and

FIG. 6 is a left side elevational view thereof.

The dominant features of my design reside in the full line showings of the drawing. The conventional electric cord in FIGS. 2 through 6 is broken away for convenience of illustration.

I claim:

The ornamental design for a combined illuminable display sign and clock, substantially as shown and described.
